DESIGN FOR A LODGE FINGER RING

Harry F. Everline, Philadelphia, Pa., assignor to Supreme Council Order of the Amaranth,
Brooklyn, N. Y., a corporation of New York

Application September 8, 1933. Serial No. 49,223

Term of patent 14 years

To all whom it may concern:

Be it known that I, HARRY F. EVERLINE, a citizen of the United States, residing at Philadelphia, in the county of Philadelphia and State of Pennsylvania, have invented a new, original, and ornamental Design for a Lodge Finger Ring, of which the following is a specification, reference being had to the accompanying drawing forming part thereof.

Fig. I is a top plan view of a lodge finger ring showing my new design; and,

Fig. II is a side elevational view of the ring.

I claim:

The ornamental design for a lodge finger ring, as shown.

HARRY F. EVERLINE,
